UNITED STATES PATENT OFFICE.

REYNOLD H. KIEBLER, OF CHICAGO, ILLINOIS.

FORM REGISTERING AND LINE-UP MEANS.

1,158,133.

Specification of Letters Patent.

Patented Oct. 26, 1915.

Application filed March 20, 1915. Serial No. 15,684.

To all whom it may concern:

Be it known that I, REYNOLD H. KIEBLER, a citizen of the United States, residing at Chicago, county of Cook, State of Illinois, 5 have invented a certain new and useful Improvement in Form Registering and Line-Up Means; and declare the following to be a full, clear, and exact description of the same, such as will enable others skilled in the art to 10 which it pertains to make and use the same, reference being had to the accompanying drawings, which form a part of this specification.

In making up forms containing a considerable number of pages, much time is 15 lost in ordinary printing establishments in lining up the pages properly so as to secure the desired margin on all sides.

My invention has for its object to provide 20 a few simple devices adapted to be attached and detached quickly to the chases in which the typographical matter is locked up and support guiding threads, strings, wires or the like in the positions for locating the 25 several edges of the pages according to which the pages are ordinarily adjusted.

The various features of novelty whereby 30 my invention is characterized will herein-after be pointed out with particularity in the claims; but, for a full understanding of my invention and of its object and advantages, reference may be had to the following detailed description taken in connection with the accompanying drawings, wherein:

35 Figure 1 is a plan view of a sixteen page form with my lining attachments in position thereon; Fig. 2 is a section taken approximately on line 2—2 of Fig. 1; Fig. 3 is a view similar to Fig. 1 of a corner of a 40 form including a chase having no cross bars; Fig. 4 is a top plan view on an enlarged scale of a fragment of the chase shown in Fig. 1 with the base line marking device in position; Fig. 5 is a section taken approximately on line 5—5 of Fig. 4; Fig. 6 is a section taken approximately on line 6—6 of Fig. 4; Fig. 7 is a plan view on an enlarged scale of the base line marking device shown in Fig. 3, a portion of the chase being 45 included; Fig. 8 is a section approximately on line 8—8 of Fig. 7; Fig. 9 is a top plan view on an enlarged scale of one of the line holders; Fig. 10 is a side elevation of the device shown in Fig. 9, the chase being 50 shown in section; Fig. 11 is a view looking

toward the left from the right hand end of Fig. 10; Fig. 12 is a view similar to Fig. 9 showing a double line holding device; and Fig. 13 is a view looking toward the left from the right hand end of Fig. 12.

In alining the pages, either the cross bars of the chase where a chase with cross bars is employed, or two of the adjacent sides of the chase, where there are no cross bars, are made to serve as the base lines from which the measurements are taken. In accordance with my invention, I provide a simple device for locating abutments upon the upper surface of the outside members of the chase lying in the plane of the members or surfaces which serve as the base lines. In addition I provide adjustable clamps adapted to be positioned by measuring from said abutments and to support lines of any suitable sort stretched across the chase and defining the edges of the pages from which adjustments are to be made. I prefer to make use of two separate styles of starting-point marking devices, the one to be used where the chase contains cross bars and the other where there are no cross bars.

In Figs. 4, 5 and 6 I have illustrated the starting point marking or locating device adapted to be used where there are cross bars. This device consists of two flat metal bars, 1, 1, having between their ends comparatively broad downwardly projecting pieces, 2, the combined width of the two bars being not greater than the narrowest cross bar ordinarily found in chases of a size 90 large enough to make my invention useful in connection therewith, and the members, 2, 2, being shorter than the thickness of such cross bars. The members 1 are made long enough so that when they are laid 95 upon a cross bar, 3, of a chase with the members 2 lying on the inner side of the outer member, 4, of the chase adjacent to one end of the cross bar, the outer ends of the members 1 project across the upper face 100 of the chase member 4. Furthermore, the parts are so proportioned that the outer edges of the two bars 1 lie exactly in the plane of the corresponding faces of the cross bar and consequently mark these planes 105 above the chase member 4 when the members 2 engage with the sides of the cross bar. In addition there is a suitable clamp for holding the abutment members 1 firmly in place. In the arrangement shown, this clamp con- 110

sists of two parallel pieces, 5 and 6, to the upper end of one of which is fixed a plate, 7, extending laterally on one side across the top of the member 6. A screw threaded rod, 8, is fixed at one end to the member 6 and passes through the member 5, a thumb nut, 9, being arranged on the rod on the outer side of the member 5. The plate 7 is provided with an elongated slot, 10, extending lengthwise thereof and through this slot extends a screw, 11, which is screwed down into the top of the member 6. The members 5 and 6 therefore constitute two parallel jaws of a clamp which may be drawn tightly together by means of the screw 8 and be locked by means of the screw 11. The screw 8 is of course located far enough above the lower ends of the members 5 and 6 to permit the lower ends of the latter members to pass down beside the pieces 2 on the abutment devices.

In Figs. 7 and 8 I have illustrated a modified abutment device for use on a chase having no cross bars. This device consists of a long flat bar, 12, carried by a suitable clamp which may be slipped down over one of the sides 13 of the chase, locating the inner edge of the bar in the plane of the inner edge of the member 13 of the chase and allowing one end to project across the top of one of the other members 14 of the chase, if the device is located in one corner of the chase. In the arrangement shown, the clamping device consists of two U-shaped metal pieces, 15 and 16, having the member 12 secured in corresponding corners thereof so that when the legs at these corners engage with the inner face of the member 13 of the chase, the corresponding edge of the member 12 lies in the plane of this face. Through the other legs of the members 15 and 16 extend screws, 17, which are adapted to be screwed against the outer edges or faces of the member 13.

The line supporting device is shown in Figs. 9, 10 and 11. In the form illustrated, it consists of a simple U-shaped jaw, 20, having on the outer side of one of the arms a plate, 21, projecting beyond the yoke member of the jaw and provided with one or more seats for a thread, string, wire or other line arranged very slightly higher than type high from the lower end. Through the other arm of the jaw extends a screw, 22, adapted to be tightened against the outer edge of the chase member on which the device is placed, the jaw of course being placed on the chase member with the arms or legs extending downwardly and the yoke resting on the upper surface. In addition there is at some convenient point on the device a means for securing the end of a line passing through the seats or one of them in the plate 21. In the arrangement shown this means consists of a thumb screw, 23, extending vertically into the top of the outer leg of the jaw. I

have stated that the plate 21 contains one or more seats and, while one seat is sufficient, I prefer to have a series as this will make it much easier to adjust the device. In the arrangement shown, the seats are in the form of small holes, 24, extending through the plate 21 with their axes parallel with the yoke of the jaw. The holes are preferably enlarged at their ends so as not to leave any sharp edges which will cut or fray a line passing through them. The seats, that is the holes 24, are preferably spaced according to the printer's scale, their centers being a pica or preferably half a pica apart, the first and preferably also the last of the seats 80 being aligned with the side edges of the yoke member of the jaw.

Where the heads of two pages, as will hereinafter be described, come close together, instead of using two of the devices shown in Figs. 9 to 11, the work of lining up the form may be facilitated by using a double device such as shown in Figs. 12 and 13. Referring to these two figures, 25, 25 indicate two jaws identical with the jaws 20, and 26, 26 represent two plate members corresponding to the plate 21 but made in a single piece considerably wider than the plate 21 so as to space the members 25 apart. The outer arms of the members 25 are connected together by a cross piece, 27, thereby tying the two devices into a single rigid unit.

The manner of using my improvements is as follows: Where a chase is used having cross bars, 3 and 30, and frame members, 4 and 40, as illustrated in Fig. 1, the abutment device shown in Figs. 4 to 6 is first placed on one of the cross bars 3, adjacent to one of the outer members 4 and the line holders 20 are then placed in position on the latter member with at least one of the line receiving seats in each instance spaced apart from the corresponding edge of the abutment a distance equal to the distance at which one of the edges of the corresponding printed page is to be from the base line which is the near side of the cross bar on which the abutment is located. Thus in the arrangement shown in Fig. 1 of the drawing, assuming that the page denoted by the rectangle A has its head at the right hand end while the page indicated by the rectangle B has its head at the left hand end: one of the line holders will be located on the bar 4 by laying a spacing device consisting of a piece of furniture slightly shorter than the distance between the head of the sheet A and the cross bar 3 against the abutment device and then abutting the line holder against the free end of the spacing device. In the same way the second line holder for locating the line of the head of the page B may be set by using the first of the line holders as a starting point or by measuring directly from the 130

abutment device. Two other line holders, for the pages C and D, in the arrangement shown, are attached to the chase and then the abutment device is removed to the opposite 5 side of the chase so as to permit the location of line holding devices directly opposite those on the other side. The abutment device may then be shifted in succession to the ends of the cross bar 30 and the requisite 10 number of line holders located on the members 40 of the chase. After the line holders have been placed in position, suitable lines are stretched from each holder to the opposite holder. The lines are threaded through 15 the openings in the line holders, being simply knotted or provided with an enlargement or shoulder of any suitable sort at one end so as to prevent them from pulling through the line holders and being drawn taut across the 20 chase and held at their other ends under the thumb screws, 23, the lines, 31, in the drawing being shown as having knots, 32, at one end. By placing the line seats in the holders so that they will be just a little above the 25 plane of the printing surface which is indicated by the dotted line 33 in Fig. 2, the lines are held close enough to the printing surface to permit accurate adjustment of the pages to be made without interfering with the 30 manipulations which are necessary in the form in order to bring about the proper adjustment and alinement of the pages. After the pages have been accurately alined, the attachments are removed, this being an operation requiring but a moment. 35

Instead of using the two devices for locating the heads of the pages A and B, where the margins are not too great, the single double unit illustrated in Figs. 12 and 13 40 may conveniently be employed.

Where the chase has no cross bars, the abutment device illustrated in Figs. 7 and 8 may be used, the outer members of the chase 45 serving as the starting or base lines and the abutment device being first arranged as shown in Fig. 3 with the bar, 12, extending across the top of the member 14 of the chase. All of the necessary line holding devices on the member 14 are located from the abutment bar 12. The abutment device is then 50 moved to the opposite bar and the operation of locating the line holding device completed. In the same way the line holding devices are located on the member 13 and 55 the chase directly opposite by placing the abutment device at opposite ends of the member 14, with the bar 13 extending transversely across the other bars.

It will thus be seen that I have provided 60 a very simple means for accurately locating and placing lines for guiding workmen in alining pages in a form without employing means which will interfere with the easy and convenient manipulation of the furniture necessary to bring about adjustment 65

and alinement of the pages. It will also be seen that the lines may be roughly located by using spacing from measuring pieces for the holders which are graduated relative to each other only in multiples of five picas or 70 any other number, the final adjustment being secured by selecting the proper seat or opening in the line holder.

While I have illustrated and described in detail only preferred forms of my various 75 attachments, I do not desire to be limited to the specific constructions thus illustrated and described, but intend to cover all embodiments which come within the terms of the definitions of my invention constituting the 80 appended claims.

I claim:

1. In combination, a chase, a series of detachable line-holding devices adapted to be secured directly upon the chase, and a starting-point marking device adapted to be detachably mounted on the chase to afford a starting point from which to space said line-holding devices. 85
2. In combination, a chase, a series of holders detachably secured directly upon said chase, and page-locating lines stretched across the chase between said holders. 90
3. The combination with a chase, of a starting-point marking device comprising a member adapted to be secured to one piece of the chase and extend across the top of an adjacent outer piece of the chase with an edge in the plane of one of the side faces of the first-mentioned piece. 95

4. The combination with a chase, of an abutment, and means for attaching said abutment to one member of the chase with a portion of the abutment overlying the top of an adjacent outer chase member and having an edge of said portion lying in the plane of one side of the first-mentioned member. 105

5. A line-holder comprising a clamp adapted to be secured on and overlie one of the outer members of a chase, the clamp having a seat for a line at one end, and a line fastening device at the other end of the clamp. 110

6. A line-holder comprising a clamp adapted to be secured on and overlie one of the outer members of a chase, said clamp having a seat for a line so located as to bring the seat slightly higher than type-high when the clamp is placed on a chase. 115

7. A line holder comprising a clamp adapted to be secured on and overlie one of the other members of a chase, said clamp having a row of seats for a line so located as to bring the row of seats slightly higher than type-high when the clamp is placed on a chase. 125

8. A line holder comprising a clamp adapted to be secured on and overlie one of the outer members of a chase, said clamp 130

- having a row of line-receiving seats extending transversely across the same at uniform distances apart.
9. A line holder comprising a clamp adapted to overlie and be secured upon one of the outer members of a chase, said clamp having a transverse upwardly-projecting portion provided with a series of perforations extending in a row across the same.
10. 10. A starting point marker comprising a long flat bar and means for clamping the bar upon a chase so as to overlie two adjacent chase members with one long edge of the bar extending across one of said members in the plane of a side face of the other of said members.
11. A line holder comprising a clamp adapted to be secured on and overlie one of the members of a chase or other supporting device, said clamp having a row of line-receiving seats extending transversely across the same at uniform distances apart and having in rear of said seats a line fastening device.
12. A line holder comprising a clamp adapted to overlie and be secured upon one of the outer members of a chase or other support, said clamp having a transverse upwardly-projecting portion provided with a series of holes extending through the same, and a line fastening device arranged behind said upwardly-projecting portion.
13. The combination with a chase having a cross bar, of a clamp detachably connected to one of the cross bars, said clamp having a straight-edge member lying in the plane of one of the edges of said cross bar and extending over the top of one of the outer members of the chase.
14. The combination with a chase having a cross bar, of a clamp detachably secured on said cross bar at one side of the chase, said clamp having two straight-edges lying above the cross bar in registration with the two side edges of the cross bar and extending over the top of the adjacent outer member of the chase.
15. The combination with a chase, of a clamp detachably secured on one of the members of the chase, said clamp having a straight-edge registering with one of the edges of the member on which the clamp is mounted and extending over the top of an adjacent member of the chase.
16. A line holder comprising a clamp having a jaw large enough to fit over one of the outer members of a chase, the clamp having on top thereof near one end a seat for a line, and means in rear of the seat for securing the end of a line.

In testimony whereof, I sign this specification.

REYNOLD H. KIEBLER.
